Alexander Denev

ATTORNEY

UNITED STATES PATENT OFFICE.

PAUL THAMM, OF NEW YORK, N. Y.

DESIGN FOR A WATCH OR CLOCK DIAL.

56,731.

Specification for Design.

Patented Dec. 7, 1920.

Application filed October 8, 1919. Serial No. 329,369. Term of patent 3½ years.

To all whom it may concern:

Be it known that I, PAUL THAMM, a citizen of the United States, residing at New York, in the county and State of New York, have invented a new, original, and ornamental Design for a Watch or Clock Dial, of which the following is a specification, reference being had to the accompanying drawing, forming a part thereof.

The figure is a plan view of a watch or clock dial embodying my design.

I claim:

The ornamental design for a watch or clock dial as shown.

PAUL THAMM.
